BOTTLE CAPPING MACHINE

Benjamin F. Davis and Walter H. Riedel,
St. Paul, Minn.

Application June 15, 1931. Serial No. 544,418

17 Claims. (Cl. 226—92)

Our present invention relates to bottle capping machines of the type disclosed and broadly claimed in the application of Benjamin F. Davis "Bottle capping apparatus" filed May 28, 1930, under Serial Number 456,442 and the application of Benjamin F. Davis and Walter H. Riedel "Bottle capping machine" filed December 26, 1930, under Serial Number 504,716.

The primary object of this invention is to improve the machine, in the last above identified application, by simplifying its construction and increasing its efficiency, as will hereinafter appear.

To the above end, the invention consists of the novel devices and combinations of devices hereinafter described and defined in the claims.

In the accompanying drawings, which illustrate the invention, like characters indicate like parts throughout the several views.

Referring to the drawings:

Fig. 1 is a side elevation of twin cap-forming and bottle capping heads applied to the reciprocating shaft and guide posts of a bottle filling machine and is in its bottle receiving and cap-forming position;

Fig. 2 is a view principally in central vertical section taken on the line 2—2 of Fig. 3;

Fig. 3 is a plan view of the parts as shown in Fig. 1, some parts being broken away;

Fig. 4 is a view partly in plan and partly in horizontal section taken on the irregular line 4—4 of Fig. 1;

Fig. 5 is a view principally in section taken on the irregular line 5—5 of Fig. 3;

Fig. 6 is a fragmentary detail view principally in section taken on the line 6—6 of Fig. 1, on an enlarged scale;

Fig. 7 is a view corresponding to Fig. 2 but showing the machine in a cap blank and cap positioning position;

Fig. 8 is a view corresponding to Fig. 1 but showing the machine in a cap-applying position; and

Fig. 9 is a view corresponding to Fig. 2 but showing the parts as positioned in Fig. 8.

While the present invention is shown applied to a commercial bottle filling machine in place of its twin bottle capping head, it will be understood that the same may be designed as an individual cap-forming and bottle capping machine.

Of the parts of the commercial bottle filling machine shown, certain parts thereof being only diagrammatically illustrated, it is important to note the feed table 10, vertically movable shaft 11,

and pair of fixed upright guide posts 12. These guide posts 12 extend upward through the feed table 10 and are connected thereabove by upper and lower tie members 13 and 14, respectively. The upper tie member 13 is vertically adjustable on the guide posts 12, for a purpose that will hereinafter appear, and rigidly secured where adjusted on said posts by hand-screws 15 which have threaded engagement with the tie member 13 and impinge against the guide posts 12. The lower tie member 14 rests on the top of the feed table 10 and is rigidly secured to the guide posts 12 by split clamping collars 16 formed with said tie member. The shaft 11, which is midway between the two guide posts 12 and parallel thereto, is mounted for endwise reciprocatory movement in bearings formed with the tie members 13 and 14. For the purpose of this case it is not thought necessary to illustrate the driving connections for reciprocating the shaft 11.

A cross-head 17 is slidably mounted on the guide posts 12 and has a recessed seat 18 for a twin capping head, not shown, secured by a pair of nut-equipped bolts 19 to said cross-head. This cross-head 17 is connected to the shaft 11 for relative longitudinal adjustment by a long screw-rod 20 which has threaded engagement with said cross-head. The upper end of the screw-rod 20 is turnably mounted in a bearing 21 fixed on the upper end of the shaft 11. Said screw-rod 20 is held against endwise movement in the bearing 21 by a collar 22, below said bearing bracket, and the hub of a hand-crank 23 above said bearing bracket and by which hand-crank the screw-rod 20 may be turned. The collar 22 and hub of the hand-crank 23 are secured by pins to the screw-rod 20. By operating the screw-rod 20 the capping head may be raised or lowered and the cross-tie member 13 adjusted on the guide posts 12 for different sized bottles, for instance, half-pints, pints, and quarts.

Milk or cream bottles X are successively moved onto the feed table 10 to bottle filling positions and thereafter moved to bottle capping positions by well-known mechanism which, for the purpose of this case, it will not be necessary to illustrate. From a broad view point the bottles X may be placed on the feed table 10 in bottle capping positions by hand or otherwise.

Referring now in detail to the invention which includes twin capping heads that are laterally spaced from each other and each thereof includes a base 24 on which a block 25 is secured by screws. The twin capping heads are individually and detachably secured to the cross-head 17.

by having formed therewith bearing brackets 26 mounted in the cross-head seat 18 and rigidly secured by the bolts 19 to the cross-head 17. These bolts 19 extend through horizontal slots 5 in the bearing brackets 26 which permit common horizontal adjustment of the twin capping heads on the cross-head 17. A long tie-bolt 27, which extends through apertured lugs on the bearing brackets 26, clamps said bearing brackets together and prevents lateral separation thereof.

Formed in each block 25 is an outer cylindrical magazine 28, a center or intermediate die cylinder 29, and an inner cap-applying cylinder 30. The axes of the magazine 28 and the two 15 cylinders 29 and 30 are all in the same vertical plane and the planes of the twin capping heads are parallel.

As the construction and action of each capping head is identical, the one with the other; it is 20 thought that the description of the one will suffice for the other.

The magazine 28 is designed to hold a stack of cap blanks Y which normally rest on the base 24 and which magazine has formed in its wall a 25 vertical slot which extends from the top to the bottom thereof and affords a sight and finger opening 31. The lowermost blanks Y are successively moved by an ejector slide 33 edgewise from the magazine 28 through a passageway 32 in the wall of the block 25 between said magazine and the die cylinder 29 and into cap-forming position in said cylinder. This ejector slide 33 is in the form of a flat plate which slidably rests on the base 24 and has in its inner end a segmental notch 33' of substantially the same diameter as the cap blanks Y.

On the top of the ejector slide 33 at the longitudinal edges thereof is a pair of fixed rails 34 cross-connected at the outer end of said slide. 40 These rails 34 also act as a reinforcement for the ejector slide 33 to prevent warping thereof. The rails 34 work in a pair of diametrically opposite ways 35 in the sides of the block 25 at the magazine 28 and hold the inner end of the 45 ejector slide 33 for straight line sliding movement on the base 24. Said ejector slide 33 is guided at its outer end for straight line sliding movement and held against lifting movement from the base 24 by a cross-head 36. This cross-head 36 extends transversely under the base 24 and is fixed at its ends to the under side of the ejector slide 33 outward of the base 24 and slidably engages said base at its longitudinal edges and under side. The intermediate portion of 55 the cross-head 36 is recessed to reduce the frictional contact between said head and base 24.

Normally the ejector slide 33 is retracted and the stack of cap blanks Y rest on the base 24, see Fig. 2. The ejector slide 33 is reciprocated 60 by connections, as will presently appear.

Caps Z are formed from the blanks Y by a pair of cooperating dies 37 and 38. Each cap Z has a depressed central portion, which forms the cap proper and rests on the seat therefore in the 65 neck of the bottle X, and an outstanding sanitary flange which extends over the top of the bottle and covers the same.

The lower die 37 includes a fixed ring 39, removably mounted in a recessed seat therefore 70, in the top of the base 24, and a receding annular block 40 within said ring and having at its axis a depending stem 41 which works through a hole in the base 24 and is guided thereby. On the lower end of the stem 41 is a nut which normally engages the under side of the base 24 as

a stop that limits the lifting movement of the block 40.

A coiled spring 42 encircling the stem 41 is compressed between the base 24 and block 40 and normally holds said block in its uppermost position. The upper face of the base 24 is recessed to receive the lower end portion of the spring 42. The upper face of the block 40 is normally flush with the upper face of the ring 39 so that the blanks Y will freely slide over said block and ring during its movement into the die chamber 29. A pair of upstanding positioning pins 43 on the die ring 39 center the blanks Y as they are moved by the ejector 33 from the stack into the die cylinder 29. These positioning pins 43 are on opposite sides of the center line of travel of a cap blank Y to the dies 37 and 38 and forward of the center of said dies.

The distance between the positioning pins 43 is slightly less than the diameter of a cap blank Y so that during the movement of said blank to the dies 37 and 38 the same is pinched between the positioning pins 43 and frictionally held thereby to prevent said blank from following the ejector slide 33 during its retracting movement.

The upper die 38 is in the form of a plunger mounted in the die cylinder 29 for reciprocatory movement and comprises an outer sleeve 44 and a central core 45 which have a limited relative 105 axial sliding movement. Said die core 45 normally extends completely through the sleeve 44 and arranged to enter the ring 39, depress the block 40 and form the depressed central portion of the cap Z. The die sleeve 44 is arranged to 110 cooperate with the die ring 39 and form the sanitary flange of the cap Z. The die core 45 has, intermediate of its ends, an annular shoulder 46 which normally rests on an internal annular ledge 47 on the die sleeve 44 and axially 115 positions said sleeve and core in cap-forming relation. The purpose of this loose connection between the die sleeve 44 and die core 45 is to cause the die sleeve 44 to move downward with the die core 45 and permit an initial return or 120 upward movement of said core in respect to the die sleeve 44 and cause said core to act as a stripper to remove a formed cap Z from the die 38. During the return movement of the die 38 the block 40 is raised by its spring 42, which was 125 placed under tension during the formation of the cap Z, and lifts the cap from the die ring 39.

The lifting movement of the die core 45 in the die sleeve 44 during its cap-stripping action is limited by a transverse pin 48 anchored at 130 its ends in said sleeve and extends through a vertical slot 49 in the die core 45. A coiled spring 50 compressed between the under side of the pin 48 and a screw-plug 51 in the lower end of the die core 45 normally and yieldingly holds 135 the die core 45 with its shoulder 46 on the ledge 47 of the die sleeve 44. During the lifting movement of the die 38 inertia and friction will hold the die sleeve 44 while the die core 45, which is being positively moved, will compress the spring 50 and move upward in said sleeve until the die core 45 at the lower ends of the slots 49 engage the pin 48 and thereby lifts the die sleeve 44 therewith.

Extending through the base 24 in axial alignment with the cap-applying cylinder 30 is an annular passageway 52 for the neck of a bottle X on the feed table 10. Projecting into the passageway 52 from the walls thereof, and intermediate of its ends, is an internal annular stop 140

80

ledge 53. The walls of the passageway 52 from the outer edge of the stop ledge 53 diverge outwardly and downwardly and afford a bottle centering surface 54. The passageway 52, above the stop ledge 53, is of the same diameter as the cap-applying cylinder 30.

Within the cap-applying cylinder 30 is a reciprocating bottle-aligning and clamping sleeve 55 held against rotation in said cylinder by a key 10 and keyway 56. The sleeve 55 normally rests on the stop ledge 53 and is yieldingly held by a coiled spring 57 compressed between the top of the sleeve 55 and a screw-cap 58 which closes the upper end of the cylinder 30. In the lower end 15 of the sleeve 55 is an internal bottle-aligning and holding seat 59 arranged to receive the outer top portion of a bottle and align the same with said sleeve and hold the bottle against lateral movement in respect thereto.

Within the sleeve 55 is a reciprocating plunger 60 having at its axis an upwardly projecting stem 61 which works in a seat therefore in the cap 58. A coiled spring 62, encircling the stem 61, is compressed between the cap 58 and plunger 60, normally and yieldingly holds said plunger projected. A nut 63 applied to the stem 61 outward of the cap 58 is arranged to engage said cap as a base of resistance and limit the projecting movement of the plunger 60. The lower end portion of the plunger 60 is shaped 30 to enter the depressed central portion of the cap Z and engage the entire upper surface of the cap and press the same into the neck of a bottle on the seat therefore in said neck and also press its sanitary flange onto the top of a bottle.

The caps Z as they are formed and stripped from the dies 37 and 38 are successively moved edgewise from the cap-forming cylinder 29 through a passageway 64 in the wall of the block 25 between the cylinders 29 and 30, through a passageway 65 in the sleeve 55 and into said sleeve. When the sleeve 55 is resting on the stop shoulder 53 its passageway 65 is in alignment with the passageway 64. The internal diameter of the sleeve 55 is substantially the same as the external diameter of the sanitary flange of the cap Z and the engagement of said flange with the internal wall of the sleeve 55 centers the cap in said sleeve and in respect to 50 the bottle X.

An ejector bar 66 is provided for moving the cap Z from the cap-forming cylinder 29 to the cap-applying cylinder 30. This ejector bar 66 extends transversely over the base 24 and slidably rests thereon for reciprocating movement. The under side of the ejector bar 66 intermediate of its ends is provided with a notch of such size as to permit said bar to pass over the positioning pins 43. This ejector bar 66 above its 55 notch is arranged to engage a cap Z at the edge of its sanitary flange and move the same in advance thereof.

Referring now to the connections for reciprocating the ejector slide 33, the same includes a pair of bell-cranks 67 pivoted at their elbows to a pair of brackets 68 secured one to each side of the block 25. The depending arms of the bell-cranks 67 extend vertically downward, are relatively long and connected by a pair of horizontal links 69 to the sides of the cross-head 36. The other arms of the bell-cranks 67 are very short, extend horizontally away from the ejector slide 33, are bifurcated and have formed on the upper prongs thereof, substantially vertical cam surfaces 70 and on the lower prongs

thereof substantially horizontal cam surfaces 71. Cooperating with each pair of cam surfaces 70 and 71 is a cam roller 72. The two cam rollers 72 are journaled on a pair of axially aligned trunnions on the lower end portions 80 of the legs of a yoke 73 that transversely straddles the block 25. This yoke 73 is carried by the stem 61 which extends through a bore at the center of the transverse portion of said yoke.

A nut 74 applied to the stem 61 outward of 85 the yoke 73 is arranged to engage said yoke and limit the upward movement of the yoke thereon. The stem 61 above the nut 63 is reduced in diameter to form a shoulder 75 and a coiled spring 76 encircling the stem 61 is compressed 90 between said shoulder and the under side of the transverse portion of the yoke 73. The purpose of the spring 76 is to cushion the action between the cam rollers 72 and the bell-cranks 67. The legs of the reciprocating yoke 73 are 95 held by anti-friction guide rollers 77 against the action of the cam rollers 72 on the cam surfaces 70 and 71. These guide rollers 77 are journaled on the block 25. It will be noted that the brackets 68 may be adjusted on the block 100 25 toward or from the guide rollers 77. Obviously, the engagement of the cam rollers 72 with the cam surfaces 70 and 71 oscillates the bell-cranks 67 which, in turn, reciprocate the ejector slide 33.

The die 38 is reciprocated by the following connections, actuated by the capping head during its reciprocating movement by the shaft 11, to wit: a long pair of parallel horizontal levers 78 positioned one on each side of the yoke 110 73 are pivoted at one of their ends for vertical swinging movement to a pair of upstanding lugs 79 formed with the block 25, one on each side of the magazine 28. The other ends of the levers 78 are movably connected to the upper 115 cross-tie member 13 by short depending links 80. A vertical link 81 is pivoted at its upper end to and between the levers 78 for horizontal swinging movement parallel to said levers and its lower end is pivoted to a short heavy stem 120 82 on the die core 45. This stem 82 has on its lower end a screw stud 83 which is screwed into the top of the die core 45 at the axis thereof to connect the same.

The ejector bar 66 is reciprocated from the 125 connections which reciprocate the die 38 by a pair of cam rollers 84 and a pair of bell-cranks 85. Said cam rollers 84 are journaled on the outer ends of a horizontal shaft 86 which extends transversely over said die. This shaft 130 86 extends through a bore in the stem 82 and long bosses on the sides thereof and through deep notches 87 in the top of the block 25 at the sides of the cap-forming cylinder 29. The bell-cranks 85 are substantially identical with 135 the bell-cranks 67 and arranged in the same manner. Short links 88 connect the lower ends of the long arms of the bell-cranks 85 to the ends of the ejector bar 66. In the bifurcated short arms of the bell-cranks 85 are upper cam surfaces 89 and lower cam surfaces 90. The bell-cranks 85 are pivoted to bearing brackets 91 similar to the bearing brackets 62 and secured to the sides of the block 25 in the same manner.

From the above description it is evident that 140 it is necessary to place a bottle under the capping head and cause the same to function and when there is no bottle under the capping head the ejector slide is not operated to feed a cap 145 150

blank to the dies 37 and 38, and hence, no cap is formed.

Operation

15 Figs. 1 to 6, inclusive, show the capping head in cap-forming position wherein said head is in its uppermost position and a bottle X is positioned on the feed table 10 under the cap-applying cylinder 30, the ejector slide 33 is retracted and positioned to engage the lowermost blank Y in the magazine 28 and move the same into the cap-forming cylinder 29 during the next operation of the machine, the dies 37 and 38 are in cap-forming relation with a cap Z therebetween, the ejector bar 66 is retracted and positioned to engage the cap Z and move the same into the cap-applying cylinder 30 during the next operation of the machine while the cap-applying plunger is at its limit of downward movement within the head. During the initial downward movement of the capping head by the shaft 11 the levers 78 are actuated by the downward movement of the capping head, in respect to the stationary cross-tie member 13 to which they are attached, and move the upper die 38 downward at a slower speed than the downward movement of the capping head by the shaft 11 and thereby cause the dies 37 and 38 to separate and at which time the formed cap is stripped from said dies. During this initial downward movement of the capping head the cam rollers 84 move between the opposing cam surfaces 89 and 90 and the ejector bar 66 remains idle as well as the cap-applying plunger 60 and connections therefrom to the ejector slide 33.

20 Just prior to the engagements of the sleeve 55 with the bottle X and while said sleeve is moving with the capping head and its passageway 65 is in alignment with the passageway 64, the cam surfaces 89 are brought into engagement with the cam rollers 84 which swing the bell-cranks 85 and project the ejector bar 66 which moves the cap Z through the passageways 64 and 65 and into the sleeve 55 which center the same.

25 During the intermediate downward movement of the capping head and while the sleeve 55 is resting on the bottle X, the spring 57 is being compressed and the cam surfaces 71 are moved out of engagement with the cam rollers 72 which are held stationary by the connections to the plunger 60 and the cam surfaces 70 are brought into engagement with said cam rollers 72, swing the bell-cranks 67 on their pivots to project the ejector slide 33 and move the lowermost blank Y through the passageway 32 and onto the lower die 37 and into contact with the positioning pins 43. The latter part of the downward movement of the capping head brings the plunger 60 onto the positioned cap Z in sleeve 55, and said cap is pressed by said plunger into the neck of the bottle and onto the seat therefor.

30 At the completion of the application of the cap to the bottle X the shaft 11 starts the return or lifting movement of the capping head. During the initial lifting movement of the capping head the compressed springs 57 and 62 hold the sleeve 55, and the cap-applying plunger 60 on the bottle X while the tension of said springs is gradually released until stop 63, engages cap 58, and until the stop ledge 53 engages said sleeve and lifts the same from the bottle.

35 While the movement of the capping head, in respect to the plunger 60 is taking place, the

cam surfaces 71 on the bell-cranks 67, which are moving upward with the block 25, are brought into engagement with the cam rollers 72, which are held stationary by the connection from said plunger, operate the bell-cranks 67 and retract the ejector slide 33. The ejector slide 33, as the same is retracted, moves from under the stack of cap blanks Y and causes said stack to drop onto the base 24 and thereby position the lowermost blank in front of the ejector slide 33 to be engaged and moved thereby to the dies 37-38 during its next projecting movement. Following the retractive movement of the ejector slide 33 the cam surfaces 90, are brought into engagement with the cam rollers 84, both of which are being moved upward but at different speeds, and operate the bell-cranks 85 to retract the ejector bar 66. During the final lifting movement of the capping head the dies 37 and 38, which are approaching each other at different speeds, engage the blank on the die 37 and form the cap Z.

40 From the above description it is evident that no two operations of the capping head take place at the same time, thus relieving the capping head from undue strains and at the same time produce sufficient power to perform each operation with a smooth and easy action. The moving parts of the capping head are silent in their action and the levers 78, which operate the die 38, are positive in their action and produce their greatest leverage between the dies 37 and 38 during the formation of the cap thereby.

45 From the time a cap blank Y leaves the magazine 28 until it is completed in cap form and positioned in the cap-applying chamber 30, it moves in a straight line and in the same horizontal plane.

What we claim is:

1. In a machine of the class described, a member, a reciprocating head having cap-applying means and a die cylinder in the head, means for reciprocating the head with respect to said member, a pair of cap-forming dies in the die cylinder, one of which is relatively movable, operative connections between the head and said member for reciprocating the movable die during the reciprocation of said head, and means for feeding caps from the dies to the cap-applying means.

2. In a machine of the class described, a reciprocating head having cap-applying means and a die cylinder in the head, a member supported independently of said head, means for reciprocating the head, a pair of cap-forming dies in the die cylinder, one of which is relatively movable, connections for reciprocating the movable die including a lever pivoted to the head and connected to said member and arranged to be actuated by the movement of the head in respect to the member, said connections being arranged to operate the movable die at a different speed from that of the head, and means for feeding caps from the dies to the cap-applying means.

3. In a machine of the class described, a head having cap-applying means, a die cylinder, means for vertically reciprocating the head, a pair of cap-forming dies in the die cylinder, one of which is relatively movable, said movable die including a sleeve and a core in the sleeve, said sleeve and core being relatively movable, positive means for reciprocating the core, a spring normally holding the sleeve on the core in cap-

- forming relation, said core being arranged to positively move the sleeve therewith during its projecting movement, said spring being arranged to yield and permit the core to move in respect to the sleeve during its retracting movement, and means for feeding caps from the dies to the cap-applying means. 5
4. In a machine of the class described, a head having a cap blank magazine, a cap-forming cylinder and a cap-applying cylinder, cap-forming dies in the cap-forming cylinder, an ejector for feeding cap blanks from the magazine to the dies, a spring-projected plunger in the cap-applying cylinder and having a stem, a yoke carried by the stem and having a pair of cam rollers on its legs, a pair of bell-crank pivoted to the head, links connecting one of the arms of the bell-crank to the ejector, the other arms of the bell-crank having opposing cam surfaces, said cam rollers being arranged to alternately engage the cam surfaces to operate the bell-crank. 10
5. In a machine of the class described, a vertically movable head having a cap blank magazine, a cap-forming cylinder and a cap-applying cylinder, means for reciprocating the head, upper and lower cap-forming dies in the cap-forming cylinder, one of which is relatively movable, connections for reciprocating the movable die actuated by the reciprocation of the head, a cap seating plunger in the cap applying cylinder, an ejector for feeding cap blanks from the magazine to the dies, means for reciprocating the ejector, a second ejector for feeding caps from the dies to the cap applying cylinder, and means for actuating the last noted ejector. 15
6. A bottle capping machine including a head reciprocatory toward and from capping relation with a bottle, a member with which said head is relatively movable, said head provided with a holder for flat cap blanks, cooperating dies relatively movable to successively shape said blanks into dished annular flanged caps, and a cap applying cylinder provided with a spring projected cap seating plunger, operative connections between said head and said member whereby said dies are forcibly brought together to form a flat blank into said cap and whereby said dies are separated, means for successively feeding blanks to said dies when said dies are separated, means for feeding formed caps from said dies to said cap applying cylinder, and mechanism for cooperation with a bottle in capping position to effect the application of the cap to the bottle and the actuation of the means for feeding a flat blank to the dies. 20
7. In a bottle capping machine, in combination, a head, means for reciprocating the same toward and from a bottle in capping position, said head including a holder for a stack of flat cap blanks, a pair of cooperating dies for successively shaping the flat blanks into annularly flanged dished form, and a cap applying cylinder provided with a spring projected plunger for seating caps in and on the bottle heads, means for successively feeding flat blanks from the holder to the dies, means for feeding formed caps from the dies to the cap applying cylinder, and mechanism whereby said various means and the dies are operated in sequence by the reciprocation of said head. 25
8. Bottle capping apparatus, including a capping head; mechanism for moving said head on its capping and return strokes; an independently supported member with respect to which said
- head has relative movement; said head provided with spring projected yielding cap applying means for capping a bottle located in capping position and relation with respect to said head, die mechanism for shaping flat sheet material into a shaped cap for delivery to operative position with respect to said applying means; and power multiplying lever mechanism between said member and head for operating said die mechanism to shape a cap and release the same on a head operation cycle consisting of a capping and return stroke. 30
9. Bottle capping apparatus including a capping head for applying shaped caps to bottles located in capping position; means for operating said head on its capping and return strokes; die mechanism for shaping a bottle cap from a flat blank for delivery for capping a bottle at capping position by said head; means for delivering a blank to said die mechanism; a spring-projected member carried by said head and adapted to engage a bottle in capping position during the capping stroke of said head and to be thereby halted while the head continues on its capping stroke and begins on its return stroke; and actuating means for said blank delivery means brought into action by the relative movement between said head and said halted member. 35
10. In bottle capping machinery, a member, a capping head movable on its operative and return strokes with respect to said member and providing cap-applying means; head actuating mechanism; cap forming dies carried by said head including a relatively movable die; operative connections between said member and said head for actuating said movable die by relative movement between said head and said member; and means actuated by said operative connections for feeding caps from said dies to said cap-applying means. 40
11. In cap applying machinery, a head provided with cap-applying means; a member supported independently of said head; means for causing operative relative capping and return movements between said member and head; cap forming dies carried by said head including a relatively movable die; actuating connections for the movable die including a lever operatively connected to both the member and head and actuated by relative movements thereof, said actuating connections actuating the movable die at a different speed from that of the relative movement between head and member; feed means for delivering caps from the dies to said cap applying means; and means actuated by said die actuating connections for operating said feed means. 45
12. In bottle-capping machinery, a capping head provided with a cap blank magazine, cap forming die mechanism and a cap-applying chamber; a member supported independently of said head; actuating mechanism for causing relative cap applying and return movements between said member and head; ejectors for feeding cap blanks from the magazine to the die mechanism and from the die mechanism to said cap applying chamber; a yieldingly-projected relatively movable cap-applying plunger operative in said chamber; operative connections between said head and said member for actuating said die mechanism; and actuating connections from said plunger to said ejectors for operating the same. 50
13. In bottle-capping machinery, a capping

head provided with a cap blank magazine, cap forming die mechanism and a cap-applying chamber; a member supported independently of said head; actuating mechanism for causing relative cap applying and return movements between said member and head; ejectors for feeding cap blanks from the magazine to the die mechanism and from the die mechanism to said cap applying chamber; a yieldingly-projected 5 relatively movable cap-applying plunger operative in said chamber; operative connections between said head and said member for actuating said die mechanism; and actuating connections from said plunger to said ejectors for operating the same, including a cushioning spring 10 operatively included therein.

14. In bottle-capping machinery, a capping head provided with a cap blank magazine, cap-forming die mechanism and a cap-applying chamber; feed means for delivering blanks from the magazine to said die mechanism; a yieldingly-projected cap-applying plunger operative in said chamber and provided with a stem; a yoke carried by and movable longitudinally of 15 the stem, a spring yieldingly pressing the yoke in one direction on the stem, said yoke having a leg carrying a roller; a swingable lever carried by said head and having an arm with opposing cam surfaces alternatively operatively engaged by said roller; and operative connections between another arm of said lever and said feed means.

15. In bottle-capping machinery, a capping head movable on its capping and return strokes and provided with cap applying means, and cap forming die mechanism; a member supported independently of said head; head actuating mechanism; die mechanism actuating means including differential lever mechanism connected to both the head and said member; feed means for delivering caps from said die mechanism to said cap applying means; and means for actuating said feed means including a lever having an arm operatively connected to said feed means 40 and another arm having opposing cam surfaces 45

and a roller moving with and actuated by said die mechanism; and alternately operatively engaging said cam surfaces.

16. In combination, in a bottle capping machine, a head having cap applying means and a die mechanism for shaping caps to be applied to the bottle heads by said means; a member; means for causing relative reciprocatory movement between said head and member; said die mechanism including a relatively movable die; connections including a lever operatively coupled to the head, movable die and member to actuate said movable die on its relative operative and return strokes by the relative movements between the head and member; an ejector for delivering caps from the die mechanism to the cap applying means; and means for actuating said ejector including a bell crank pivoted on the head having an arm operatively coupled to the ejector and another arm operatively coupled to said movable die operating connections through the medium of the cam roller and opposing cooperating cam surfaces. 80 85 90 95

17. In combination, in bottle capping machinery, a head; a support for an abutment-constituting bottle in capping position; means for causing operative bottle capping and return relative movements between said head and said bottle in capping position; a die mechanism for successively shaping and releasing caps from flat blanks; a holder for flat cap blanks; a cap-applying cylinder provided with a spring-projected plunger for applying said caps to the bottle heads; means for feeding blanks from said holder to said die mechanism; means for feeding shaped caps from the die mechanism to said cap-applying cylinder; and mechanisms operated by said relative movements between said head and said bottle in capping position for actuating said die mechanism and said 100 105 110 115 various feeding means in sequence one after the other.
